(57) **CLAIM**

The ornamental design for a trim for gaming machine, as shown and described.

DESCRIPTION

FIG. 1 is an isometric view of the trim for gaming machine, showing our new design;

FIG. 2 is a front elevational view;

FIG. 3 is a right elevational view; and,

FIG. 4 is a left elevational view.

The dashed lines in the figures show the environment of the present design and are not part of the present design. The portions of the article that are not shown in the drawings form no part of the claimed design.
